(57) **CLAIM**

The ornamental design for a disc top closure with wave contour, as shown and described.

DESCRIPTION

FIG. 1 is a top view of a disc top closure according to the present invention.

FIG. 2 is a left side view of the disc top closure of FIG. 1; the right side view is a mirror image.

FIG. 3 is a front view of the disc top closure of FIG. 1.

FIG. 4 is a rear view of the disc top closure of FIG. 1; and,

FIG. 5 is a bottom view of the disc top closure of FIG. 1. The portions of the drawings appearing in broken lines are for environment only and do not form a part of the claimed design.
